TURFING TOOL

Harry Kittner, New York, N. Y., assignor to Heirloom Needle Work Guild, Inc., a corporation of New York

Application October 26, 1948, Serial No. 56,572

1 Claim. (Cl. 112—80)

1

This invention relates to a turfing tool for forming a series of loops through the surface of a fabric, as for forming rugs or the like.

Where the conventional turfing tool, which usually includes a hollow handle portion with a tubular needle through which the yarn extends and which is pointed at one end, is used to form loops in fabric, especially when rough fabric such as burlap is used, where the turfing tool is gripped adjacent the end of the handle from which the tubular needle extends, as the needle is forced through the burlap to form a loop in the yarn, the user's fingers and knuckles are apt to be rubbed on the burlap and after repeated use, may result in abrasions and bleeding with possibility of infection.

It is accordingly among the objects of the invention to provide a turfing tool of the above type that may be used repeatedly, at a relatively high rate of speed without special care or precaution, to form loops in even the roughest fabric without likelihood of injury to the hands of the user.

Another object is to provide a tool that is simple in construction having but the minimum number of parts, that is capable of easy adjustment to give the desired length of loop, is sturdy and efficient in use, is not likely to get out of order and can be manufactured at very low cost.

In the accompanying drawings in which are shown one or more of various possible embodiments of the several features of the invention,

Fig. 1 is a perspective view of the turfing tool in use, and,

Fig. 2 is a central longitudinal section of the turfing tool alone, taken along line 2—2 of Fig. 1.

Referring now to the drawings, the tool comprises a handle 10 of any suitable material such as wood or plastic, having a grip portion 11 with a shank portion 12, an annular flange 13 at the lower end of the shank portion and a reduced nose portion 14, said flange portion extending laterally outward from said shank with the intersection between said shank and said flange forming substantially a right angle. The handle is provided with a central passage 15 which extends longitudinally therethrough and in which is positioned the conventional type of needle 16 which is of tubular form and pointed at one end as at 17 with an eye 26 therethrough adjacent the point. The passage 15 is slightly larger in diameter than the maximum diameter of the needle to be used in conjunction with the handle and the passage 15 is open at the rear end 20 so

2

that the yarn may be passed through the handle and through the tubular needle.

For connecting the needle to the handle so that it is adjustable lengthwise thereof, the reduced nose portion 14 of the handle has a ferrule 18 securely affixed therearound, having a transversely extending threaded opening 19 therein aligned with a transverse opening extending through nose portion 14 into passage 15. By means of a screw 21 threaded into said opening the needle may be rigidly affixed in said handle with the pointed end 17 projecting therefrom to the extent desired.

15 Encompassing the shank portion 12 of said handle 10 and seated on the upper edge 22 of annular flange 13 is a shield 23 which preferably comprises a disc of resilient material such as rubber having a central hole 24 of diameter smaller than that of flange 13 and also smaller than the shank 12 of the handle.

15 In assembling the tool the rubber disc or shield 23 is stretched so that flange 13 may pass through opening 24 therein. When the tension on shield 23 is released, it will contract, securely 25 to grip the shank portion 12 of the handle immediately above flange 13.

20 In the use of the tool, the yarn is passed through the opening 20 in the upper end of the handle and then through passage 15, the bore 25 of the needle and through the eye 26 thereof as shown. The grip portion 11 of the handle is held as shown in Fig. 1 in the manner of a pencil or pen with the finger tips resting on the top of the rubber disc or shield 23. To form the loop in the fabric, the latter is stretched on a suitable frame 27 so that it is maintained in taut condition as shown in Fig. 1.

25 The user thereupon forces the needle through the fabric until the ferrule 18 abuts thereagainst and then quickly withdraws the needle until the tip 17 thereof is slightly above the fabric thereby forming the loop. The needle is thereupon moved over slightly and the operation repeated as often as required. As the user's fingers are 30 adjacent the rubber disc 23, they will not come in contact with the rough fabric which might otherwise occur at the rapid rate at which the loop forming operation is generally performed and hence the finger tips and knuckles of the user will not be rubbed which might cause abrasions with possible danger of infection.

35 Thus by the use of the rubber disc or shield 23 on the handle of the tool, the user is able to make a large number of loops at a relatively high rate of speed inasmuch as no special care need

be taken to prevent injury to the hands with the resultant convenience, speed and safety.

As many changes could be made in the above construction and many apparently widely different embodiments of this invention could be made without departing from the scope of the claim, it is intended that all matter contained in the above description or shown in the accompanying drawings shall be interpreted as illustrative and not in a limiting sense.

Having thus described my invention what I claim as new and desire to secure by Letters Patent of the United States is:

A turfing tool comprising a handle having a grip portion and a shank portion, an annular flange at the end of said shank portion extending laterally outward therefrom, the intersection between said shank portion and said flange forming substantially a right angle and a reduced nose portion extending beyond said annular flange, a passageway extending longitudinally through said handle, a pointed tubular turfing needle positioned in said passageway adjustable lengthwise thereof and extending from said nose portion adjacent said flange, a shield of greater diameter than said handle comprising a resilient rubber disc having a central opening

therein of smaller diameter than said flange and of smaller diameter than said shank portion, seated on the upper face of said flange and encompassing said shank portion, a sleeve encompassing said reduced nose portion and affixed thereto, said sleeve having a transverse threaded opening therein aligned with a transverse opening extending through said nose portion and a set screw threaded into said opening whereby the longitudinal position of said needle may be adjusted.

HARRY KITTNER.
